UNITED STATES PATENT OFFICE.

ROBERT LEVENSON, OF NEW YORK, N. Y., ASSIGNOR OF ONE-HALF TO MORRIS ECKER, OF NEW YORK, N. Y.

CHAIR FOR X-RAY WORK.

Application filed July 28, 1921. Serial No. 488,204.

To all whom it may concern:

Be it known that I, ROBERT LEVENSON, a citizen of the United States, and a resident of the borough of Manhattan, city, county, and State of New York, have invented certain new and useful Improvements in Chairs for X-Ray Work, of which the following is a specification.

This invention relates to improvements in chairs for X-ray work.

One of the objects of this invention is to produce a chair for use with X-ray apparatus which will provide means for the accurate positioning and supporting of the patient's head in all the varying positions necessary to procure proper X-ray photographs of different portions thereof.

Another object of my invention is to provide a chair of the character specified which may be manufactured at a low cost, which will be sanitary and simple in operation.

Another object of my invention is to provide means for engaging and guiding the patient's head at three points, namely, at opposite sides and the top so as to limit movement in all directions and aid in precise positioning and supporting thereof during the operation of taking the X-ray photographs.

Another object of my invention is to provide means in combination with a chair seat for supporting the body and a head-rest for positioning the head, of an adjustable arm-engaging member at one side of the chair for engaging the elbow of the patient to assist in retaining his arm in any suitable elevated position.

Another object of my invention is to provide a head-rest for X-ray work embodying hinged members which will be capable of assuming positions in angular relation to each other for contact with the opposite sides of the back of the head when in vertical or substantially vertical position, and which members may be flattened out into alignment or registration with each other for contact with and support of one side of the head in horizontal or inclined position.

Another object is to utilize a cap pad in combination with such foldable hinged members for engaging the top of the patient's head in either position and to assist in guiding and positioning the same.

Another object of my invention is to provide a sanitary head-rest composed of a transparent material such as glass backed

up by a sheet of material impervious to X-rays, such as sheet lead.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a front elevation of a chair embodying my invention;

Fig. 2 is a side elevation of the chair shown in Fig. 1;

Fig. 3 is a plan view of the chair shown in Figs. 1 and 2;

Fig. 4 is a view in side elevation of a portion of the back of the chair and head-rest when its members are flattened out and swung into horizontal position;

Fig. 5 is an enlarged top plan view of the head-rest and adjusting means for the leaves thereof;

Fig. 6 is an enlarged rear elevation of the head-rest and adjusting means therefor;

Fig. 7 is a cross-section through the head-rest on the line 7—7 of Fig. 1.

Referring now to these drawings, 1 indicates the base or supporting frame of the chair which is of the usual type and is preferably supported by leg members 2. Said base has, as illustrated, a centrally-located screw-threaded socket 3 in which is threaded a screw 4, on the upper end of which is mounted a chair-seat 5 preferably having the form shown in plan in Fig. 3. Said chair seat has, as shown, rigid vertically-disposed back 6 fixed thereto. Two sockets 7 and 8 are mounted on the rear side of this back 6. Through the sockets 7 and 8 extends an adjusting rod or bar 9, at the upper end of which is mounted a head-rest 10 which is pivoted to swing about a horizontal pivot 10a. The bar 9 and sockets are preferably so positioned in relation to the rear of the chair that the head-rest 10, when in vertical position, will register or be in vertical alignment with the back of the chair 6. As illustrated, the head-rest 10 comprises two hinged members or leaves 11 and 12 respectively which are hinged together on a hinge pintle 13 which, as illustrated, is supported at opposite ends in a

yoke-bracket 14. The pivotal movement of the hinged leaves 11 and 12 on the pintle 13 is preferably controlled by arcuate arms 15 and 16 fixed at one end to the said leaves 5 and having the opposite free ends extending through a slot 17 formed in the yoke bracket 14. As illustrated, these arms overlap at their ends and are simultaneously fastened in place by a screw 18 provided with a knob 10 or handle 19. These arms permit the pivotal swinging of the leaves to any degree of relative angular inclination to each other or into registry or alignment with each other. It will be understood that it is desirable in taking X-rays of the jaws for dental work to have the leaves turned at an angle to each other so as to form rests for the opposite sides of the back of the head and also to retain the head rest in substantially vertical alignment with the back of the chair.

In practice, I prefer also to provide means for contacting with the top of the head to limit the movement in upward or vertically swinging position and for this purpose I provide the cap pad 20 which preferably extends from the yoke bracket outwardly and centrally above the leaves of the head-rest and forms a stop for the top of the head 25 to assist in positioning the same and to guard against upward or vertically swinging movement.

It is frequently necessary to take X-rays when the head is in substantially horizontal 35 or inclined position with the side of the face supported, and for this purpose I have provided for the vertical swinging into horizontal position of the head rest and the flattening out of the hinged leaf members. The bodily movement of the head-rest 40 is preferably accomplished by pivotally mounting the supporting bracket 14 and for this purpose I provide knuckles 21 and 22 respectively on the bracket 14 and rod 9 45 respectively and pass therethrough a tightening screw 23 provided with a knob or handle 24. In order to determine the exact degree of inclination in any given case, I preferably provide on one of the knuckles 50 or socket of the bracket a series of graduating marks 25 and on the rod I provide a pointer or indicating mark 26, thus enabling the operator to adjust his head-rest to any exact degree of inclination desired between 55 the horizontal and vertical.

In chairs of this character it is frequently necessary to cause a patient to place his finger in his mouth for the purpose of retaining therein a film in order to procure X-rays of the teeth and jaw. A nervous patient frequently causes the film to be moved out of position and it is, therefore, desirable to support the patient's arm during the retention of the film in his mouth 60 and for this purpose I have provided arm-

supporting pads 27 each of which is adjustable vertically so as to contact with and engage one of the arms of the patient to support the same in any position fixed by the operator, while the other arm pad is lowered into contact with the seat and out of the way. Each pad 27 is mounted upon a long rod 28 which extends through a bore 29 in the seat of the chair 5 so that each rod may be moved independently from a position contacting with the chair seat to a position adjacent to the top of the chair back. Each of the said adjusting rods 28 may be locked in position by tightening screws 30 having knobs or handles 31.

It is desirable in work of this character that the head rest and chair be sanitary and easily cleaned and also that the material of the head rest be such as to resist the passage of X-rays to serve as protection 85 against such rays, and to this end each of the said leaves is preferably composed of a frame 11^a, a backing 11^b of lead or like X-ray resisting material and a surface layer of glass 11^c or similar material.

Having described my invention, I claim:

1. An X-ray chair embodying, in combination, a base, a seat rotatably mounted thereon, a back fixed to said seat, a head-rest mounted on said back to have vertical sliding movement and composed of a plurality of flat hinged members movable relatively to each other from angular disposition into a single plane and means for moving 10 said head-rest bodily in an arcuate path from vertical to horizontal position.

2. An X-ray chair embodying, in combination, a base, a seat rotatably mounted thereon, a back fixed to said seat, a head-rest mounted on said back to have vertical sliding movement and composed of a plurality of flat hinged members movable relatively to each other from angular disposition into a single plane, means for moving said head-rest bodily in an arcuate path from vertical to horizontal position and a cap pad mounted on said head-rest adapted to contact with the top of the head of a person seated therein.

3. An X-ray chair embodying, in combination, a base, a seat rotatably mounted thereon, a back fixed to said seat, a head-rest mounted on said back to have vertical sliding movement and composed of a plurality of flat hinged members movable relatively to each other from angular disposition into a single plane, means for moving said head-rest bodily in an arcuate path from vertical to horizontal position and an adjustable arm support for engaging one arm of the person seated in said chair to retain the same in elevated position.

4. An X-ray chair, embodying, in combination, a base, a seat rotatably mounted

thereon, a back fixed to said seat, a rod mounted on said back to have vertical sliding movement; a bracket adjustably mounted on said rod to swing rearwardly and forwardly in relation to said chair back; a hinge pintle mounted in said bracket; and leaves pivotally mounted on said pintle, and means for fastening said leaves in varying positions.

10 5. An X-ray chair, embodying, in combination, a base, a seat rotatably mounted thereon, a back fixed to said seat, a rod mounted on said back to have vertical sliding movement; a bracket adjustably mounted on said rod to swing rearwardly and forwardly in relation to said chair back; a hinge pintle mounted in said bracket; leaves pivotally mounted on said pintle each having a backing of a material impervious to 20 X-rays and a facing of glassy material.

6. An X-ray chair embodying, in combination, a base, a seat rotatably mounted thereon, a back fixed to said seat, a rod mounted on said back to have vertical sliding movement; a bracket adjustably mounted on said rod to swing rearwardly and forwardly in relation to said chair back; a hinge pintle mounted in said bracket; two flat leaves pivotally mounted on said pintle, 25 means for fastening said leaves in varying positions and a cap pad mounted on said head-rest above said hinge pintle.

7. An X-ray chair embodying, in com-

bination, a base, a seat rotatably mounted thereon, a back fixed to said seat, a rod 35 mounted on said back to have vertical sliding movement; a bracket adjustably mounted on said rod to swing rearwardly and forwardly in relation to said chair back; a hinge pintle mounted in said bracket; leaves 40 pivotally mounted on said pintle each having a backing of a material impervious to X-rays and a facing of glassy material and a cap pad mounted on said head-rest above said hinge pintle.

8. An X-ray chair embodying, in combination, a base, a seat rotatably mounted thereon, a back fixed to said seat, a rod mounted on said back to have vertical sliding movement; a bracket adjustably mounted on said rod to swing rearwardly and forwardly in relation to said chair back; a hinge pintle mounted in said bracket; two flat leaves pivotally mounted on said pintle, 50 two arc-shaped bars fixed to each leaf at one end and having the opposite free ends passing through a common slot and means for fastening said free ends to fix the position of said leaves in relation to each other.

In witness whereof, I have signed my 60 name to the foregoing specification in the presence of two subscribing witnesses.

ROBERT LEVENSON.
